Primary Examiner — T. Chase Nelson*Assistant Examiner* — Jonathan J Han(74) *Attorney, Agent, or Firm* — Mark S Hubert(57) **CLAIM**

I claim the ornamental design for the door jamb repair device, as shown and described.

DESCRIPTION

FIG. 1 is a front perspective view of the door jamb repair device;

FIG. 2 is a front view of the door jamb repair device;

FIG. 3 is top view of the door jamb repair device;

FIG. 4 is a left-side view of door jamb repair device;

FIG. 5 is a rear view of the door jamb repair device;

FIG. 6 is a right-side view of the door jamb repair device;

and,

FIG. 7 is a bottom view of the door jamb repair device.
